UNITED STATES PATENT OFFICE.

ALFRED L. DAY, OF BROOKLINE, MASSACHUSETTS, ASSIGNOR TO DAY PERFORATOR COMPANY, A VOLUNTARY ASSOCIATION OF MASSACHUSETTS.

PERFORATING MACHINE.

Application filed May 5, 1920. Serial No. 379,162.

To all whom it may concern:

Be it known that I, ALFRED L. DAY, a citizen of the United States, residing at Brookline, county of Norfolk, State of Massachusetts, have invented an Improvement in Perforating Machines, of which the following description, in connection with the accompanying drawing, is a specification, like characters on the drawing representing like parts.

This invention relates to perforating machines and particularly to perforating machines of that type which have matrices adjustable into different positions for perforating different characters. One of the objects of the invention is to provide a perforating machine of this type with means for automatically restoring the matrices to zero position after each perforating operation. This feature of the invention is particularly useful when the perforating machine is used in a line of work where at each operation a different number or character is perforated. In this case it is necessary for the operator to set or adjust the matrices before beginning each operation, and in doing this it is a great convenience if all the matrices are restored to zero position at the end of each operation so that the setting is performed from the zero position.

Another object of my invention is to provide an improved form of sector-shaped matrix which can be readily made in the form of a die casting.

Another object of the invention is to provide a perforating machine with means for making on a strip or ribbon a record of all the perforated characters made at different actuations of the machine.

Other objects of the invention are to improve generally perforating machines, all as will be more fully hereinafter set forth.

In order to give an understanding of my invention, I have illustrated in the drawings a selected embodiment thereof which will now be described, after which the novel features will be pointed out in the appended claims.

In the drawings, Fig. 1 is a side view of a perforating machine embodying my invention with a portion broken out;

Fig. 2 is a section on the line 2—2, Fig. 1; Fig. 3 is a section on the line 3—3, Fig. 2; Fig. 4 is a section on the line 4—4, Fig. 1. 55 1 indicates the base of the machine which

is provided with a throat or space 2 to receive the paper to be perforated. The bottom of this throat 2 is formed by a die-plate 3 which is provided with a plurality of groups of perforations adapted to receive the perforating punches 4. These perforating punches are arranged in groups, as usual in perforating machines of this type, and each group has a sufficient number of punches so that by selectively depressing the punches of each group any desired figure or character may be perforated in the paper. The punches are selectively actuated by means of matrices 5 which are carried by a vertically-movable head 6, the latter being shown as pivoted to the base 1 at 7. Each matrix is provided with a plurality of groups of punch-receiving recesses, the recesses of each group being arranged so that the blank spaces between the various recesses correspond to some particular figure, letter or other character. When any matrix is adjusted to bring any group of recesses over the punches and the head 6 is then depressed, the upper end of those punches which correspond to the recesses will enter the recesses and will not be depressed, while the other punches which correspond to the places where there are no recesses will be depressed and will thus perforate the paper. The blank spaces between the recesses of each group are arranged to produce the desired character, this being a common expedient in perforating machines of this type.

The head 6 may be given its vertical movement in any suitable way. I have herein shown said head as having an operating shaft 7 journaled therein which is provided with a handle 8 for rotating it. This shaft 7 has fast thereon two eccentrics 9, the eccentric straps 10 of which have arms 11 extending therefrom which are pivotally connected to the base frame at 12. These eccentrics and the eccentric arms are shown as located on the outside of the base frame and head. Since each eccentric is fast on the shaft 7, the rotation of the shaft will obviously raise and lower the head by an amount equal to the throw of the eccentrics.

Each matrix 5 is sector shaped and it is provided with a hub portion 13 which is loosely mounted on the shaft 7. The body of each matrix is provided with a plurality of groups of recesses 14 to co-operate with the punches 4 in perforating the character

in the paper. The face of the matrix in which the recesses are received is on the arc of a circle having the axis of the shaft 7 as its center, and each matrix is provided with a curved extension 15 also formed on the arc of a circle. This extension is provided at its end with a thumb-piece or projection 16 by which the matrix can be adjusted about the shaft 7 to bring any group of recesses 14 into line with the group of punches. The head 6 is provided with the cylindrical portion 17 in which the matrices are received, and this cylindrical portion is provided with a cover plate 18 which overlies the extensions 15 and which is provided with slots 19 through which the projections 16 pass. The face of each extension 15 is provided with indicating characters 20 which assist the operator in adjusting the matrix. When any matrix is adjusted so that any indicating character 20 comes into position just at the lower edge 21 of the slot 18, then the matrix is properly adjusted to actuate the required punches to punch in the paper a character corresponding to said indicating character. These sector-shaped matrices are light in weight and can be readily made in the form of die castings if desired.

Means are provided for yieldingly holding each matrix in any adjusted position. This is herein accomplished by making the head with a bar 22 which extends transversely there-across and is situated inside of the extensions 15. This bar supports a plurality of spring-pressed retainers herein shown in the form of balls 23 which engage the inner faces of the extensions, and the extensions are provided with recesses 24 which receive the retaining balls 23 and thus yieldingly hold the matrices in place. This form of retainer does not interfere at all with the adjustment of the matrix, but it provides means for yieldingly and frictionally holding each matrix in its adjusted position. When any matrix is moved from one position to another, the corresponding retaining ball 23 will click over the recesses 24 and the dropping of the ball into the successive recesses furnishes the operator with suitable indication as to when any group of apertures is directly over the punches.

As stated above, another feature of my invention relates to means for automatically restoring all the matrices to zero position at each operation of the machine. Fig. 1 shows the matrix in its zero position. The restoring of the matrices is accomplished by means of a restoring bar 25 which extends across the machine adjacent the hubs 13 and which co-operates with projections or lugs 26 formed on the hubs of the matrices. This restoring bar 25 is normally in the position shown in Fig. 1 and when the matrices are

in zero position, the projections 26 are in the position shown in Fig. 1. When any matrix is adjusted, the projection 26 is moved toward the restoring bar and when the matrices are all adjusted the projections 26 will assume various positions between that shown in Fig. 1 and the restoring bar. Means are provided for giving the restoring bar a movement about the axis of the shaft 7 just after the punches have been depressed, and during such movement of the restoring bar it engages the projections 26 of the matrices and brings them all back to the position shown in Fig. 1. When the matrices are fully restored, the restoring bar 75 is automatically returned to the position shown in Fig. 1. This restoring bar is carried by two collars 27 which are loosely mounted on the shaft 7, and it is acted upon by a spring 28 which tends to hold it in the 80 position shown in Figs. 1 and 2. The restoring bar has at one end an extension 29 which operates in a slot 50 formed in the side wall of the head 6. The shaft 7 carries a spring-pressed dog 31 which is movable radially in a recess 32 and is acted on by a suitable spring 33 which tends to force it outwardly. The outward movement is limited by a suitable pin 34 operating in a slot in an extension 35. This dog 31 is provided with a notch 36 to receive the extension 29 of the restoring bar 25, and it is also formed with the bevel or cam face 30. When the machine is at rest after having completed its cycle of operations the restoring bar will be in the position shown in Figs. 1 and 2, and the shaft 7 will be situated so that the dog 31 is at the upper side of the shaft. After the paper to be perforated has been placed in the mouth 2, the shaft is rotated in the direction of the arrow, Figs. 1 and 3, and during the first half revolution, the eccentrics 9 operate to depress the head thereby causing the punches to make the desired perforations. When the shaft has been rotated through about three-quarters of a revolution, the head has been lifted by the eccentrics sufficiently to free the punches from the matrices, and at this time the cam surface 30 of the dog comes into engagement 100 with the extension 29. During continued rotation, the dog wipes under the extension 29 and is depressed into the recess 32 and when the notch 36 comes opposite said extension the dog will be moved outwardly 105 under the action of the spring 33 thereby to cause said extension to enter the recess. The restoring bar at this time becomes locked to the shaft so that further rotation of the shaft carries the restoring bar with it. As 110 the locking bar moves upwardly it engages the projections 26 of the matrices which have been set and restores them to their zero position shown in Fig. 1. Just at the time that the matrices are fully restored, the cam 115

face 30 of the dog 31 engages the projection 37 formed on the head 6, and this engagement causes the dog to be depressed thereby to become disengaged from the extension 29. 5 As soon as the dog is thus disengaged from said extension the spring 28 returns the restoring bar to the position shown in Fig. 1, and this occurs just when the head is at its highest elevation. This completes the 10 cycle of operations and the shaft is left in this position until the next paper is to be perforated. It will thus be seen that during each rotation of the shaft 7 the head 6 is depressed thereby operating the punches to 15 make the desired perforation and the matrices are automatically restored to their zero position. In using the machine, therefore, the operator simply has to first set the matrices to perforate the desired number, and 20 then insert the paper to be perforated in the throat 2 and give the handle 8 one complete revolution. During each rotation the desired perforations are made in the paper and the matrices are restored to zero position. 25

My invention also contemplates the provision of means for making a record on a ribbon or strip of paper of all the characters which are perforated at different actuations 30 of the machine. To accomplish this, I have provided a record ribbon 42 which is wound on two reels 43 and 44 and which passes over the die-plate 3, so that whenever the machine is actuated to perforate a character 35 in a sheet of paper that is inserted in the throat-plate, the punches will also perforate the same character in the record strip 42. Means are provided for feeding the strip with an intermittent movement so that a 40 fresh portion thereof will be brought underneath the punches at each actuation of the machine. This feeding of the strip may be accomplished in various ways, and as illustrating one way, I have shown the reel 44. 45 as having a ratchet 45 rigid therewith which is actuated by a pawl 46 carried by a pawl-carrier 47 that is loosely pivoted on the shaft 48 of the reel. The pawl-carrier is connected by a link 49 to the head 6, so that 50 as the head moves up and down to actuate the punches, the pawl-carrier will be oscillated thereby intermittently rotating the reel 45 and giving a corresponding intermittent feeding movement to the record strip 42. 55 The connection between the link 49 and the head is such that the link is not actuated until the head has risen sufficiently to free the punches from the apertures in the record strip 42, and this is provided for by employing 60 a pin-and-slot connection between the link 49 and the head 6. In this way the record strip 42 will always contain a permanent record of all characters which have been punched at every actuation of the 65 machine.

While I have illustrated a selected embodiment of my invention, I do not wish to be limited to the constructional features shown.

I claim:

1. In a perforating machine, the combination with a plurality of punches, of a settable matrix member for selectively operating the punches, means to give said matrix member its punch-actuating movement, and means to restore automatically 70 the matrix member to zero position after each punch-actuating movement.

2. In a perforating machine, the combination with a plurality of groups of punches, of a plurality of settable matrix members, 80 one for each group of punches by which the punches are selectively actuated, means to give the matrix members a punch-actuating movement, and means to restore automatically 85 the matrix members to zero position after each punch-actuating movement.

3. In a perforating machine, the combination with a plurality of punches, of a settable matrix member for selectively operating said punches, matrix-actuating mechanism to give said matrix its punch-actuating movement, and means operated by said matrix-actuating mechanism to restore the matrix to zero position. 90

4. In a perforating machine, the combination with a plurality of groups of punches, of a plurality of settable matrix members, one for each group of punches by which the punches are selectively actuated, matrix-actuating mechanism to give the matrices 100 their punch-actuating movement, and means actuated by such mechanism to restore the matrices to zero position.

5. In a perforating machine, the combination with a plurality of punches, of a settable matrix member for selectively operating said punches, means to move the matrix member toward and from the punches, a matrix-restoring member, and means to actuate the same to restore the matrix to 110 zero position while said matrix is moving away from the punches. 105

6. In a perforating machine, the combination with a base frame, of a plurality of punches mounted therein, a depressible 115 head, a shaft journaled in the head, and a segment-shaped matrix member pivotally mounted on said shaft, and having groups of apertures on its base which co-operate with the punches to punch selected characters, said matrix member having a circular extension, and a finger piece projecting therefrom and by which the matrix may be adjusted, said member being adapted to be set by a single movement into any one of a 120 plurality of different positions.

7. In a perforating machine, the combination with a base frame, of a plurality of punches carried thereby, a depressible head, a segment-shaped matrix member pivotally 125

mounted in said head and having groups of apertures on its face, said matrix member having a circular extension, a finger piece projecting from said extension through the head and by which the matrix may be adjusted, said extension having thereon indicating characters to assist in setting the matrix member.

8. In a perforating machine, the combination with a frame having a mouth into which may be placed one or more sheets of paper to be perforated, of a perforated die-plate forming the bottom of said mouth, a plurality of punches, means for selectively operating said punches to punch different characters in a sheet or sheets occupying the mouth, a record ribbon overlying said die-plate whereby the record ribbon is punched simultaneously with the sheets of paper, and means associated with the punch-operating mechanism to feed the ribbon.

9. In a perforating machine, the combination with a frame having a mouth into which may be placed one or more sheets of paper to be perforated, of a perforated die-plate forming a portion of the bottom of said mouth, a plurality of punches co-operating with said die-plate, a vertically-movable head, means to move said head, means carried by said head to selectively operate the punches, a record ribbon passing over the die-plate, and means to feed the ribbon intermittently by the vertical movement of the head.

10. In a perforating machine, the combination with a frame, of a plurality of punches mounted therein, a depressible head, a shaft journalled in the head, a sector-shaped matrix member pivotally mounted on the shaft and provided with groups of punch-receiving recesses repre-

senting characters, and also provided with a curved extension bearing indicating characters corresponding to the recesses, said segment being constructed to be moved by a single movement into position to bring any group of recesses in alignment with the punches.

11. In a perforating machine, the combination with a frame, of a plurality of punches mounted therein, a depressible head, a shaft journalled in the head, a sector-shaped matrix member pivotally mounted on the shaft and provided with groups of punch-receiving recesses representing characters, and also provided with a curved extension bearing indicating characters corresponding to the recesses, said segment being constructed to be moved by a single movement into position to bring any group of recesses in alignment with the punches, and means cooperating with the extension to frictionally hold the matrix member in any adjusted position.

12. In a perforating machine, the combination with a frame, of a plurality of punches mounted therein, a depressible head, a shaft journalled in the head, a sector-shaped matrix member pivotally mounted on the shaft and provided with groups of punch-receiving recesses representing characters, and also provided with a curved extension bearing indicating characters corresponding to the recesses, said segment being constructed to be moved by a single movement into position to bring any group of recesses in alignment with the punches, and yielding means acting against the inside of the curved extension to hold the matrix member in any adjusted position.

In testimony whereof, I have signed my name to this specification.

ALFRED L. DAY.
